No. 36,614.

Patented November 3, 1903.

UNITED STATES PATENT OFFICE.

KENNETH M. CHAPMAN, OF LAS VEGAS, TERRITORY OF NEW MEXICO.

DESIGN FOR AN ORNAMENT.

SPECIFICATION forming part of Design No. 36,614, dated November 3, 1903.

Application filed October 3, 1903. Serial No. 175,702. Term of patent 7 years.

To all whom it may concern:

Be it known that I, KENNETH M. CHAPMAN, a citizen of the United States, residing at Las Vegas, in the county of San Miguel, Territory of New Mexico, have invented a new, original, and ornamental Design for an Ornament, of which the following is a specification.

The drawings illustrate the features of the design, and therein—
10 Figure 1 is a perspective view of the ornament embodying the design. Fig. 2 is a horizontal section thereof.

What is claimed is—

The ornamental design for an ornament as herein shown. 15

In testimony whereof I affix my signature in presence of two witnesses.

KENNETH M. CHAPMAN.

Witnesses:

VERA CHAPMAN,
MARY C. CHAPMAN.
